LIQUID SAMPLER

Malcolm F. Irwin, West Chester, Pa., assignor to
Pro-Tech Inc., Malvern, Pa.

Filed Feb. 28, 1974, Ser. No. 446,919

Term of patent 14 years

Int. Cl. D10—05

U.S. Cl. D10—81

Fig. 1

Fig. 2

Fig. 4

Fig. 3

Fig. 5

FIG. 1 is a top front perspective view of a liquid sampler showing my new design with the cover closed;

FIG. 2 is a top front perspective view thereof with the cover open;

FIG. 3 is a front elevational view of FIG. 1;

FIG. 4 is a left side elevational view of FIG. 1;

FIG. 5 is a rear elevational view of FIG. 1.

The bottom, not shown, is plain, except for the protruding feet shown in elevation.

I claim:

The ornamental design for a liquid sampler, as shown and described.
